DESIGN FOR A VEHICLE TOY

Lambert A. Wise, Pittsburgh, Pa.

Application January 10, 1947, Serial No. 136,047

Term of patent 14 years

(Cl. D34—15)

To all whom it may concern:

Be it known that I, Lambert A. Wise, a citizen of the United States of America, residing at Fox Chapel, Pittsburgh 15, in the county of Allegheny and State of Pennsylvania, have invented a new, original, and ornamental Design for a Vehicle Toy, of which the following is a specification, reference being had to the accompanying drawing, forming a part thereof.

I claim:

The ornamental design for a vehicle toy, as shown.

LAMBERT A. WISE.
